UNITED STATES PATENT OFFICE.

EDGAR B. STOCKING, OF WASHINGTON, DISTRICT OF COLUMBIA.

MECHANICAL STARTER FOR AUTOMOBILES.

1,168,915.

Specification of Letters Patent. Patented Jan. 18, 1916.

Application filed May 20, 1913. Serial No. 768,894.

To all whom it may concern:

Be it known that I, EDGAR B. STOCKING, a citizen of the United States, residing at Washington, in the District of Columbia, have invented certain new and useful Improvements in Mechanical Starters for Automobiles, of which the following is a specification, reference being had therein to the accompanying drawings.

10 This invention relates to certain new and useful improvements in mechanical starters for automobiles; and has for its object, the provision of a starter by means of which the engine can be set in motion by the 15 driver from the seat of the automobile by operating a lever located adjacent the seat.

Another object of the invention is to provide a starter which can be readily placed in position in an automobile without changing the construction in any way or moving any of the parts; the same being arranged adjacent the engine shaft and having an operating member adapted to coöperate with a member carried by the engine shaft and 25 fitted to mesh with the operating member when brought into engagement therewith by the operation of the treadle.

Another object of the invention is to provide a starter which can be placed in position upon an automobile and operated without interfering with the use of the ordinary starting crank in any way.

Another object of the invention is to provide a starter so mounted that, when in operative position, it will be held firmly therein so that it is impossible for the same to be accidentally thrown into engagement with the engine shaft by the jolting of the car.

40 A still further object of the invention is to provide a starter member in the form of a gear carried by a hanger and adapted to intersect the path of travel of a coöperteing gear carried by the engine shaft when the 45 lever adjacent the seat is operated.

Another object of the invention is to provide means for automatically throwing out of mesh, the gear of the engine shaft and the gear of the starter upon a complete 50 revolution of said shaft, or upon the back firing of the engine causing a back kick, whereby a starter is provided which automatically prevents accidental injury when used by an inexperienced or a careless 55 operator.

Another and still further object of the in-

vention is to provide novel means for locking the operating or starting member *per se* in inoperative position until pressure is brought to bear upon the operating lever, 60 or it may be a treadle, which automatically releases the operating or starting member and allows the same to be drawn down into engagement with the gear of the engine shaft and then rotated; means also being 65 provided for preventing the rotation of the operating member until it has intersected the path of travel of the gear of the engine shaft and engaged therewith, so as to prevent any loss of rotary motion. 70

A still further object of the invention is to provide a starter which is automatic in operation in respect to the returning of the starter to its initial position after the treadle has been released; the starter member being spring-actuated for accomplishing 75 this result.

Another object of the invention is to provide a suitable stop for limiting the movement of the operating or starter member in 80 order to secure a suitable and easy meshing contact with the driven member on the engine shaft.

Another and further object of the invention is to provide positive means for throwing 85 the operative member out of engagement with the member of the engine shaft after the same has made a complete revolution; means also being provided for automatically locking said member in inoperative position 90 so as to allow the spring of the operating member to rewind an operating cable thereon after the treadle has been released.

Other and further objects and advantages of the invention will be hereinafter set forth 95 and the novel features thereof defined by the appended claims.

In the drawings—Figure 1, is a top plan view of an automobile showing the application of my improved construction of mechanical starter; Fig. 2, is a side elevation of an automobile showing the mechanical starter in position in dotted lines; Fig. 3, is an elevation of the starter and supporting plate, showing the starter in its locked, inoperative position ready to be operated by the pressing of a treadle; Fig. 4, is a similar view showing the operating member thrown into mesh with a gear on the engine shaft by pressing upon a treadle, said operating member being held from rotating by a pin and hook in order to prevent the rotation 105 110

of the operating member before it has intersected the path of travel of the gear of the engine shaft; Fig. 5, is a similar view showing the operating member completing its revolution so as to revolve the gear on the engine shaft in order to start the engine; Fig. 6, is a similar view showing the operating member thrown into its initial or inoperative position and locked, during the return movement of the lever or treadle; said operating member being free to rotate to rewind the operating cable thereon; Fig. 7, is a side elevation of the starter showing the gear and coupling member of the shaft in section and the ordinary starting crank in position to start the engine, the mechanical starter being also in position to start the engine. This view shows that either the mechanical or the crank starter can be used without interfering with one another; Fig. 8, is a detail elevation showing a slightly modified form of means for spring-actuating the operating member; Fig. 9, is a top plan of the same; Fig. 10, is a detail section through the operating member; and Fig. 11, is a detail of a slightly modified form of cam and hanger.

Like numerals of reference refer to like parts in the several figures of the drawings.

In the drawings, I have shown a mechanical starter especially constructed to be used in connection with a Ford machine, but it is of course understood that the same can be adapted to be used in connection with any of the well-known makes of automobiles now in use and comprises a supporting plate 1 adapted to span the engine shaft 2 having brackets 3 at its ends for securing the same to the side bars 4 of the automobile frame which is one way of mounting the supporting plate, and it is of course understood that various other means can be employed for connecting the plate to the frame or for supporting the plate in the desired position. By connecting the plate 1 in this manner to the frame, the same is held rigidly and parallel with the fan in such a position that the operating parts carried thereby which will be later described, will not interfere with any of the mechanism of the automobile to which it is applied.

The plate 1 is provided with an upwardly projecting extension 5 to one side of the fan shaft on which plate is a hanger 6 pivotally mounted upon a bearing stud 7 and secured in position thereon, preferably by cotter pins, as clearly shown. Said hanger comprises a pair of spaced side members 8 having as here shown, a mutilated gear 9 mounted between the same upon a bearing pin 10 which projects into a groove or slot 11 formed in the supporting plate 1 in order to limit the movement of the hanger in either direction, as will be later described.

The mutilated gear is provided with a groove 12 in this instance formed midway of its width in order to economize space laterally which is usually limited by the juxtaposition of the fan and the belt. In the groove 12, is seated an operating cable 13 fastened as shown at 14 and extending sidewise over the engine shaft around a guide pulley 15 and then rearwardly under the body of the vehicle and over a guide pulley 16.

Pivots mounted within the automobile under the steering wheel and adjacent the seat thereof, is a treadle 17 preferably mounted in a bearing 18 arranged upon the floor of the automobile; said treadle having a foot portion 19 which can be readily manipulated by the foot of the driver by pressing forwardly and downwardly, thereon. The treadle 17 is provided with a depending arm 20 bifurcated at its lower end in which is revolvably mounted a groove pulley 21 over which the cable 13 passes, and said cable is brought back and has its free end secured as shown at 22. By connecting the operating cable and mounting the same in this manner, the movement of the treadle is reduced in order to obtain the desired distance of travel of the arm 20 to cause the operating gear to make a sufficient portion of a complete revolution to give the engine shaft a complete revolution, as will be hereinafter fully described. The diameter of the operating gear relative to the gear on the engine shaft determines the leverage; the larger the diameter the greater the leverage and the lesser the portion of a complete revolution required to secure a complete revolution of the engine shaft.

One face of the gear 9 is provided with a pocket 23 in which is seated a helical spring 24 having one end connected to the wall of the pocket as shown at 25 and the other end is connected to a pin 26 carried by one of the side bars of the hanger in such a manner that when the cable is operated, the spring will be wound and this spring is preferably placed under tension when the gear is in inoperative position so that after the treadle has been operated and the same is released, the gear will be restored to its original position.

In order to provide means for automatically returning the operating gear to its normal inoperative position after the same has been operated to start the engine, I provide the gear with a pin 27 extending transversely therethrough; the projecting end 28 thereof, co-acting with a cam 29 secured to the plate 1 in such a position that when the hanger is moved with the gear in position to start the engine, the cam will only be engaged by the projecting end of the pin on the final movement of the operating gear so as to throw the same back into its

normal, inoperative position, after it has performed its function of starting the engine shaft. This cam may be provided with a hooked upper end 30 to limit the 5 movement of the pin carried by the gear, in which respect the hooked end forms a stop in addition to those formed by the groove 11 in the plate 1. This hooked end may therefore, be omitted as shown in 10 Fig. 11.

The opposite end 31 of the pin 27 co-acts with a spring finger 32 of a hook 33 pivotally mounted on the hanger as shown at 15 34, said hook co-acting with a pin 35 fixed to the projection 5 of the plate 1 in such a position that on the final movement of the operating gear, the pin 27 of the same co-acting with the cam, will throw the hanger back into its original position and 20 the hook will engage the pin and lock the hanger in that position; said hook being held under spring tension by a flat spring 36 carried by a stud 37 mounted upon the hanger.

25 As shown in Figs. 1, 2, 3 and 4, upon the movement of the cable by the treadle, the hook is first released in order to allow the hanger to swing upon its bearing until the operating member carried thereby is in position to rotate the engine shaft, whereby increased pressure being brought to bear upon the operating member through the medium of the cable, the projecting end 31 of the pin 27 will ride off of the spring finger 32 so as 30 to release the operating gear and allow the same to rotate. Upon the return movement of the operating member after the treadle has been released, the projecting end 31 of the pin 27 rides under the spring finger to a 35 position to release the hook in a subsequent operation. The hook being over the pin 35, the operating member will be securely held in inoperative position so as to prevent any danger of the same being accidentally 40 thrown in the path of travel of the coöperating member of the engine shaft. It will be noted that when the operating member is in mesh with the engine shaft gear, the end of the hook 33 bears against the pin 35 and 45 tends to keep both gears in mesh.

In fitting the engine shaft to coöperate with the movable starting member, I provide a clutch cup 38 with a gear 39, (which may or may not be grooved for the reception of 55 the cable), carried by a sleeve 40 extending into the clutch cup and securely fastened therein by the clutch pin 41 which is held in position therein by cotter pins 42. By this manner of fitting the engine shaft to co- 60 operate with the starting member, the construction of clutch member now in use upon automobiles is not changed and the gear is attached thereto in such a manner that the clutch head 43 of the starting crank shaft 65 44 has free movement within the same

whereby a mechanical starter is provided which does not interfere with the operation of the crank starter now in use on automobiles. This enables the engine to be started either by the mechanical starter or the crank 70 starter and in adopting the clutch cup to the engine shaft to be operated by the mechanical starter in this manner, the fan driving belt will be rotated in the same manner common to all automobiles and the same clutch 75 pin used for fastening the cup clutch in position upon the engine shaft 2; the only change being made, being the cotter pin connection for fastening the same in position therein, and as most clutch heads of the 80 crank shaft are of the shape shown, a space is provided to receive the sleeve of the gear.

As shown in Fig. 7, a flange 45 may be provided for the gear of the engine shaft; this being omitted in Figs. 3, 4, 5 and 6 in 85 order to show the gear in full lines and the flange in these figures, is shown in dotted lines.

In the modification shown in Figs. 8, 9 and 10, instead of providing the operating 90 gear 46 with a helical spring, I form the same with a groove in which is arranged a cable 47 having one end extending over a guide pulley 48 mounted in the supporting plate and connected to a coil spring 49; the other end of said cable extending in the opposite direction to the operating treadle and said cable is fastened within the grooves preferably by a staple 50 after being wound once around the same, and this construction 100 is illustrated in order to show that other forms of springs than one arranged on or in the operating gear, can be used. Both forms of spring perform the functions of returning the hanger, carrying the operating 105 gear, rewinding the cable to its original position in connection with the spring 24, and locking the parts in said position.

In the modification shown in Fig. 11, the hook 39 of the cam 29 is dispensed with, 110 which formed a stop for the hanger and the side bar of the hanger adjacent the plate is notched as shown at 51 and the cam 52 is extended as shown at 53 in such a manner that all danger of the coöperating pin carried by the operating gear riding past the end of the cam is dispensed with and a positive movement is given to the hanger to insure the hook engaging the pin so as to lock the hanger in inoperative position.

In the operation of a mechanical starter constructed as herein shown and described, assuming that the starting member is in the position shown in Fig. 3 and locked by the hook, upon pressure being placed upon the 115 treadle by the operator's foot, the cable will start the gear to rotate slightly so as to disengage the hook from the retaining pin which releases the hanger and allows the same to be drawn down into mesh with the 120 125 130

gear of the engine shaft; the projecting end 31 of the pin 27 co-acting with the spring finger 32 which prevents the gear from rotating within the hanger to any material extent, until the co-operating gears are in mesh, whereupon a continuous pressure being brought to bear upon the treadle, the gear starts to rotate against the tension of the spring carrying with it the gear of the engine shaft and as the size of the operating gear is greater than the engine shaft, a complete revolution will be given to the engine shaft by a partial revolution of the operating gear so as to insure the starting of the engine. While I have shown a mutilated gear, it is of course understood that a complete gear will operate and accomplish the same result; as is illustrated in Figs. 8, 9 and 10.

20 As the operating gear rotates, the projecting end 28 of the pin 27 comes into contact with the cam 29 which is of such a shape that it fails to act until the last teeth of the mutilated gear have engaged the teeth 25 of the gear of the engine shaft at which time, the pin rides upon the operating portion of the cam which throws the hanger back into its original position, carrying with it, the gear and as the spring hook engages 30 the pin 35 it rides over the same and embraces the pin so as to hold the hanger in the position shown in Fig. 1 with the teeth of the co-operating gears out of mesh. When the treadle is released by the operator, the 35 operating gear being out of mesh with the gear of the engine shaft and the spring wound by the operation of the treadle, the spring starts the gear to rotating in a reverse direction, so as to rewind the cable 40 thereon, and as the projecting end 31 of the pin comes into engagement with the spring finger 32 it rides under the same and assumes the position as shown in Fig. 1, in which position the operating gear is securely 45 locked in inoperative position ready to be again operated by the manipulation of the treadle.

From this description, it will be seen that the spring not only rewinds the cable upon 50 the operating gear, but also through the medium of the cams, pins and hook, automatically returns the hanger carrying the same to its original position and locks the same in that position.

55 By arranging the operating gear to one side of the gear of the engine shaft, if a back kick of the engine occurs, the hanger will be free to move in the direction of rotation of the engine shaft gear so as to 60 throw the gears out of mesh, thereby preventing any injury being done to the operator or to the starting mechanism. On the other hand, if the engine should be started before a complete revolution is given to the 65 engine shaft, the operating gear being ro-

tated thereby, would through the medium of the pin co-acting with the cam, throw the operating gear out of mesh therewith.

While I have shown and described certain details of construction in connection with my mechanical starter and manner of mounting the same in the frame of an automobile, I wish it to be understood that the manner of supporting the same and connecting the power transmitting elements such as the 75 treadle and cable, may be varied to adapt the starter to automobiles of various makes without departing from the scope of my invention. These details are not essential, as the main object of this invention is to 80 provide a mechanical starter mounted to intersect the path of travel of the gear of the engine shaft in such a manner that it will be automatically thrown out of engagement therewith by the rotation of the engine 85 shaft in either direction. In case the first of a series of cylinders of the engine is actuated by an explosion therein, the engine in its faster rotation completes the action of the starting member and of the treadle 90 and also returns the hanger to its inoperative position automatically and after this operation of the engine, the spring in winding up the cable, throws the treadle, which has been suddenly advanced by the engine, 95 back against the foot of the operator, but without injurious force and when the foot is withdrawn, it completes the winding of the cable, the hanger in the meantime, being locked in inoperative position.

I am aware that various forms of mechanical starters are in use, but in each instance, the starting mechanism is not completely thrown out of operation when not in use, and in no instance am I aware that a 105 starter has been provided which can be placed in position upon the automobile without interfering with the cranking mechanism now in use.

While I have shown and described the 110 movable starting member co-operating with a fixed member carried by the engine shaft, it is of course understood that the movable starting member would operate a movable member carried by the engine shaft in substantially the same way, and I do not wish to limit myself to the use of a movable starter in connection with a fixed co-operating member.

In previously constructed mechanical 120 starters, clutch mechanism has been employed which necessitates the movement of a member continuously by the engine shaft, such as a pawl and ratchet, while in my construction, the engine shaft is fitted with 125 a fixed member and the starting mechanism moves in the path of said fixed member when operated by a treadle and when released out of the path of said fixed member is held in inoperative position in such a man- 130

ner that it is practically impossible for the same to be accidentally thrown into inoperative position without operating the treadle.

In the drawings forming part of this application, I have shown the plate 1 connected to the frame of the vehicle by brackets 3 which are bolted to the side bars of the frame as shown in Figs. 3, 4, 5 and 6, and by providing the brackets and overlapping 10 end portions of the plate with slots arranged at right angles, the same can be adjusted in order to position the plate in respect to the engine shaft.

I claim:

15 1. A mechanical starter comprising a movable support, a starting member mounted to rotate thereon, means for moving said starting member into different positions, means for rotating said starting member 20 when in different positions in opposite directions, and means carried by said support for locking said starting member in inoperative position.

25 2. A mechanical starter having a support mounted to swing on an arc, a gear carried by said supporting member adapted to intersect the path of travel of the pinion on the engine shaft, means for moving said starting gear into engagement with the pinion on the engine shaft and for rotating said gear in one direction, and means for 30 automatically throwing said gear out of mesh with the pinion on the engine shaft by the rotation thereof at the completion 35 of its operative rotation.

3. In a mechanical starter, an engine shaft having a pinion, a revoluble starting member capable of intersecting the path of travel of said pinion on the engine shaft, a spring 40 for returning said starting member to initial position, and means coöperating with said starting member on final rotation thereof for returning said starting member to its original position.

45 4. A starting mechanism for explosive engines comprising a revolubly mounted spring-returned member mounted to move into and out of the path of a coöperating member carried by the engine shaft, a projection carried by said spring-returned member, a cam coöperating with said projection for moving said spring-returned member into inoperative position, and means for 50 automatically locking said member in inoperative position.

5. A mechanical starter having a revolubly mounted starting member adapted to move in different paths, one of said paths intersecting the path of travel of a coöperating member carried by the engine shaft, means for rotating said starting member when in engagement with the coöperating member, means for throwing said starting member out of engagement with the coöperating member, means for revolving said

starting member in a reverse direction when out of engagement with the coöperating member, and means for locking said starting member out of engagement with the coöperating member.

6. A mechanical starter, comprising a supporting plate, a hanger pivotally mounted upon said supporting plate, an operating member revolubly mounted in said hanger, a coöperating member mounted upon the engine shaft, means for automatically moving said hanger to throw said operating member out of engagement with the coöperating member, and means carried by the hanger for locking said hanger when the operating member is out of engagement with the coöperating member.

7. A mechanical starter comprising a supporting plate, a hanger pivotally mounted upon said plate, a spring-returned gear carried by said hanger, capable of moving into the path of travel of a coöperating gear carried by the engine shaft, a cable for moving said gear into engagement with the coöperating gear, a cam carried by said supporting plate, a co-acting pin carried by said gear for moving said gear out of engagement with the coöperating gear of the engine shaft, and means for automatically locking said hanger in inoperative position.

8. In a mechanical starter for explosive engines, the combination with an engine shaft having a fixed gear mounted thereon, of a revolubly mounted starting gear mounted to move into and out of the path of travel of said fixed gear, means for rotating said starting gear in one direction, means for automatically throwing said starting gear out of engagement with the gear of the engine shaft, means for locking said gear in inoperative position, and means for rotating said starting gear in a reverse direction to return the starting gear to its original position.

9. In a mechanical starter, the combination with a pinion mounted on an engine shaft, of a supporting plate adapted to span the engine shaft, a hanger mounted on said supporting plate, a gear carried by said hanger, adapted to intersect the path of travel of the pinion of the engine shaft, a cable for rotating said gear in one direction when in mesh with the pinion, means for automatically throwing said gear out of mesh, means for rotating said gear in a reverse direction, and means for locking said hanger with said gear in inoperative position.

10. A starting mechanism comprising a hanger, an engine shaft having a gear, a gear revolubly mounted in said hanger capable of co-acting with the gear of the engine shaft, a hook for holding said hanger and gear in inoperative position, said hook being provided with a spring finger, a pin car-

ried by said gear co-acting with said spring finger for releasing said hook on the initial movement of said gear to allow said gear to intersect the path of travel of the gear of the 5 engine shaft before said gear is rotated.

11. In a mechanical starter, a pinion mounted on an engine shaft, a spring-return starting member mounted to move into and out of the path of said pinion, means for holding said gear out of the path of the 10 pinion on the engine shaft, a cable for moving said gear into the path of travel of the pinion on the engine shaft, means for automatically moving said starting member out 15 of the path of the pinion on the engine shaft, and lever means for operating said cable.

12. A mechanical starter for explosion engines, in combination with an engine shaft having a gear mounted thereon, of a starting 20 gear suspended to move into and out of the path of travel of said gear, means for moving said starting gear into the path of travel of the gear of the engine shaft and for rotating said starting gear in one direction, 25 when in the path of travel of said gear, means for moving said starting gear out of the path of said gear, means for locking said starting gear out of the path of said gear, and means for rotating said starting gear in 30 a reverse direction to return the same to its initial position.

13. In a mechanical starter, a pinion carried by the engine shaft, a starting member mounted to move into and out of the path of 35 travel of said pinion, means for limiting the movement of said starting member in respect to said pinion, means for automatically throwing said starting member out of engagement with said pinion, means for locking 40 said starting member in inoperative position, a cable for rotating said starting member to release said retaining means on the initial movement of said starting member to allow said starting member to intersect the 45 path of travel of said pinion, and means for rotating said starting member in the reverse direction when in an inoperative position to re-wind the cable thereon.

14. In an automobile, the combination 50 with an engine shaft having a pinion, of a supporting plate spanning said engine shaft, a pivoted hanger carried by said supporting plate, a spring returned gear carried by said hanger, a cable wound upon said gear, a 55 hook for locking said gear out of the path of said engine shaft pinion, a pin carried by said gear for releasing said hook on its initial movement, a projection carried by said gear, and a cam arranged in the path of 60 travel of said projection for throwing said gear out of engagement with the pinion of the engine shaft.

15. In an automobile, the combination with a clutch cup and clutch pin of the engine shaft, of a sleeve arranged within said cup 65

retained by said clutch pin and provided with a pinion, and a starting member mounted to move in a path intersecting said pinion when rotating in one direction.

16. The combination with an explosion 70 engine having a shaft provided with a clutch cup, of a gear carried by said clutch cup, a starting gear capable of moving into and out of engagement with said gear, means for operating said starting gear in one direction to move said starting gear into the path of the engine shaft gear to start the engine, means for automatically throwing said starting gear out of engagement with the engine shaft gear, and means for rotating 75 said gear in a reverse direction to return said gear to its initial position and locking said gear.

17. A mechanical starter comprising a hanger having an operating gear revolvably 80 mounted therein, an engine shaft having a co-operating gear, said operating gear being capable of being moved so as to throw the operating gear in the path of travel of the co-operating gear carried by the engine shaft, 85 a spring-actuated hook for holding said hanger when moved into one position, a spring finger carried by said hook, a projection carried by said gear for releasing said hook when moved in one direction, a cable 90 for rotating said gear, and a spring for rotating said gear in a reverse direction.

18. In a mechanical starter, a pinion carried by the engine shaft, an operating gear mounted to move into and out of the path of 100 travel of the pinion carried by the engine shaft, a cable for rotating and moving said operating gear into the path of travel of said pinion on the engine shaft, a spring for rotating said gear in the reverse direction, 105 means for automatically locking said gear out of the path of the pinion on the engine shaft, and means operated by the initial movement of said gear for releasing said locking means.

19. In a mechanical starter, a pinion carried by the engine shaft, a revolvably mounted starting member mounted to move into and out of the path of travel of the pinion on the engine shaft, a hook for locking 115 said starting member in inoperative position, a pin carried by said starting member, co-operating with said hook for releasing said hook on the initial movement of said starting member, said pin holding said starting member from rotation until the same is brought into engagement with the pinion on the engine shaft.

20. A mechanical starter comprising a 120 movably mounted supporting hanger, a gear revolvably mounted in said supporting hanger capable of intersecting the path of travel of a co-operating gear carried by an engine shaft, a spring hook for locking said supporting hanger with the gear carried 125 130

thereby in inoperative position, said hook having a spring finger, and a projection carried by said operating gear co-acting with said spring finger to prevent the rotation of said gear until said gear has intersected the path of travel of the coöperating gear of the engine shaft.

21. A mechanical starter, having a revolubly mounted starting member, a movably mounted member upon which said starting member is mounted, an engine shaft having a pinion, said starting member being capable of intersecting the path of travel of the pinion carried by the engine shaft, a member for locking said movably mounted member in one position, and a projection carried by the starting member co-acting with said member for releasing the same on the initial movement of said starting member to allow said starting member to move in the path of travel of the coöperating member of the engine shaft before the same is rotated thereby.

22. A mechanical starter comprising a pivotally mounted hanger, a pinion carried by the engine shaft, a revolubly mounted spring returned starting member carried by said hanger, capable of intersecting the path of travel of the pinion on the engine shaft, positive means for throwing said starting member into inoperative position, positive locking means for said hanger when thrown into inoperative position, means actuated by the rotation of said starting member to release said locking means on an initial movement thereof, a cable for rotating said starting member against the tension of said spring, and means for limiting the movement of said hanger in respect to said pinion on the engine shaft.

23. A mechanical starter having a starting member mounted to intersect the path of travel of a pinion on an engine shaft when rotating in one direction and to subsequently travel in a different path when rotating in a reverse direction, manually operated means for rotating said starting member in one direction, spring means for rotating said starting member in a reverse direction, said starting member having a projection coöperating with means for automatically throwing said starting member out of engagement with the pinion on the engine shaft on the final rotation of said starting member.

24. A mechanical starter comprising a movable support having a revoluble starting member mounted therein, a cable for moving said support and rotating said starting member, means carried by said movable support for locking said revoluble member in an adjusted position, and means carried by said starting member for releasing said locking means.

25. In a mechanical starter, the combina-

tion with an engine shaft, having a pinion, of a movable support, a revoluble starting member carried by said support, locking means for holding said support in one position, a member carried by said starting member coöperating with said locking means for releasing said locking means on the initial movement of said starting member.

26. In a mechanical starter, the combination with an engine shaft, having a pinion, of a movable support, a revoluble starting member carried by said support capable of intersecting the path of travel of said pinion, locking means carried by said support for holding said starting member out of engagement with the pinion on the engine shaft, and means carried by said starting member coöperating with said locking means for releasing said locking means on the initial movement of said starting member.

27. In a mechanical starter, the combination with an engine shaft having a pinion, of a movable support, a revoluble starting member mounted in said support, a locking member carried by said support, manually operated means for rotating said starting member, and means carried by said starting member coöperating with said locking means for releasing said locking means on the initial movement of said starting member.

28. In a mechanical starter, the combination with an engine shaft, having a pinion, of a movable support, a revoluble spring return starting member mounted in said support, a locking member carried by said support, means for rotating said revoluble starting member, a pin carried by said starting member for releasing said locking means, and a cam arranged in the path of travel of said pin for throwing said starting member out of engagement with the pinion on the engine shaft.

29. In a mechanical starter, the combination with an engine shaft, having a pinion, of a movable support, a revoluble starting member carried by said support capable of intersecting the path of travel of the pinion on the engine shaft, locking means carried by said support for holding said starting member in inoperative position, a pin carried by said starting member coöperating with said locking means for releasing said locking means on the initial movement of said starting member, manually operated means for rotating said starting member, and means coöperating with said pin on the final rotation of said starting member for throwing said starting member out of engagement with the pinion on the engine shaft.

30. In a mechanical starter, the combination with an engine shaft, having a pinion,

of a pivoted hanger, a revoluble starting member mounted on said hanger, means carried by said hanger for automatically locking said hanger into a position to hold the 5 starting member carried thereby out of mesh with the pinion of the engine shaft, a pin carried by the starting member coöperating with said locking means for releasing the same on the initial rotation thereof, manually operated means for rotating said starting member, and means arranged in the path of travel of said pin for throwing said hanger on the final rotation of said starting member into initial position.

31. In a mechanical starter, the combination with an engine shaft having a pinion, of a movable support, a revoluble starting member carried by said support, means for moving said support to throw said revoluble 20 starting member into engagement with the pinion on the engine shaft, a fixed member, and a coöperating member carried by the revoluble starting member adapted to engage said fixed member on the final rotation 25 thereof to throw said revoluble member out of engagement with the pinion on the engine shaft.

32. In a mechanical starter, the combination with an engine shaft having a pinion, 30 of a revoluble starting member mounted to intersect the path of travel of said pinion, a fixed member, and a laterally projecting member carried by said revoluble starting member, coöperating with said fixed member 35 on a final rotation thereof to move said revoluble starting member out of engagement with the pinion on the engine shaft.

33. In a mechanical starter, the combination with an engine shaft having a pinion, 40 of a revoluble starting member mounted to intersect the path of travel of said pinion, means for locking said revoluble starting member out of engagement with the pinion on the engine shaft, and means carried by 45 said revoluble starting member to release said locking means on the initial movement of said starting member.

34. In a mechanical starter, the combination with an engine shaft having a pinion, 50 of a supporting plate spanning the engine

shaft, a hanger movably mounted upon said plate, a revoluble starting member carried by said hanger, a cable having connection with said revoluble starting member for moving said hanger to throw said starting member 55 into engagement with said pinion, and a cam carried by said supporting plate coöperating with said starting member, for throwing said starting member out of engagement with said pinion on the final rotation thereof.

35. In a mechanical starter, the combination with an engine shaft having a pinion, of a supporting plate spanning the engine shaft, a hanger movably mounted upon said plate, a revoluble starting member carried by said hanger capable of intersecting the path of travel of the pinion on the engine shaft, a cable connected to said starting member for moving said hanger and starting member into position to engage the pinion on the engine shaft, and a cam arranged upon said plate and coöperating with said starting member on the final rotation thereof for moving said starting member 75 out of engagement with the pinion on the engine shaft.

36. In a mechanical starter, the combination with an engine shaft, having a pinion, of a supporting plate spanning the engine 80 shaft, a movable hanger mounted upon said supporting plate, a starting gear revolubly mounted on said hanger, a cable having connection with said starting gear, locking means carried by said hanger coöperating 85 with retaining means carried by said plate, means carried by said gear coöperating with said locking means for releasing said locking means on the initial movement thereof, and a cam carried by said plate coöperating 90 with said starting gear on the final rotation thereof for moving said starting gear out of engagement with the pinion on the engine shaft.

In testimony whereof, I affix my signature in presence of two witnesses.

EDGAR B. STOCKING.

Witnesses:

G. J. SIMPSON,
GEO. P. WRIGHT.
